United States Patent Office

Des. 181,606
Patented Dec. 3, 1957

181,606

ORNAMENTAL METAL-WORK PANEL

Herbert E. Reid, Fort Worth, Tex., assignor to McKinley
Iron Works, Fort Worth, Tex., a partnership

Application May 23, 1957, Serial No. 46,301

Term of patent 14 years

(Cl. D54—2)

FIG. 1

FIG. 2

FIG. 3

FIG. 4

FIG. 5

Fig. 1 is an elevation of one side of an ornamental metal-work panel embodying my new design;

Fig. 2 is an edge view;

Fig. 3 is a sectional view taken on line 3—3 in Fig. 1;

Fig. 4 is an elevation of the other side face;

Fig. 5 is a top view looking downwardly at the upper end of Fig. 4.

I claim:
The ornamental design for an ornamental metal-work panel, as shown.
